Des. 206,190
Patented Nov. 8, 1966

206,190

OPTICAL CONTACT LENS

Irving N. Adler, Detroit, Mich., assignor to
Richard J. Wlodyga, Warren, Mich.

Division of design application Ser. No. 79,900, Mar. 11,
1964, now Patent No. 203,357, dated Dec. 28, 1964.
Continuation of design applications Ser. No. 87,695
and Ser. No. 87,696, Oct. 21, 1965. This application
Mar. 11, 1966, Ser. No. 2,130

Term of patent 14 years

(Cl. D57—1)

FIG. 1

FIG. 2

FIG. 3

FIG. 4

FIG. 5

FIG. 6

FIG. 7

FIG. 8

FIG. 1 is a front elevational view of an optical contact lens, showing my new design.

FIG. 2 is a cross-sectional view thereof, taken on the line 2—2 of FIG. 1.

FIG. 3 is a rear elevational view thereof.

FIG. 4 is a rear perspective view thereof.

FIG. 5 is a front elevational view of a modified form of the design shown in FIGS. 1-4.

FIG. 6 is a cross-sectional view thereof taken on the line 6—6 of FIG. 5.

FIG. 7 is a rear elevational view thereof.

FIG. 8 is a rear perspective view thereof.

This is a division of application Ser. No. D.79,900 filed March 11, 1964, now design Patent No. D.203,357, dated December 28, 1964; and is a continuation of design applications D.87,695 and D.87,696, both filed October 21, 1965.

I claim:

The ornamental design for an optical contact lens, substantially as shown and described.
